AQUATIC TOW DISC

Michael Del Vecchio, 140 Regent Ave.,
Providence, R.I. 02908

Filed Aug. 27, 1973, Ser. No. 391,986

Term of patent 14 years

Int. Cl. D21—02

U.S. Cl. D34—42

FIG. 1

FIG. 2

FIG. 3

FIG. 4

FIG. 5

FIG. 6

FIG. 1 is a perspective view of an aquatic tow disc showing my new design;

FIG. 2 is a side elevational view thereof;

FIG. 3 is a top plan view thereof;

FIG. 4 is a bottom plan view thereof;

FIG. 5 is a front elevational view thereof; and

FIG. 6 is a rear elevational view thereof.

I claim:

The ornamental design for an aquatic tow disc, substantially as shown.
